DESIGN FOR A RADIO CABINET OR THE LIKE

George F. Bates, Brooklyn, N. Y.

Application September 3, 1941, Serial No. 103,147

Term of patent 7 years

To all whom it may concern:

Be it known that I, George F. Bates, a citizen of the United States, residing at Brooklyn, in the county of Kings and State of New York, have invented a new, original, and ornamental Design for a Radio Cabinet or the like, of which the following is a specification, reference being had to the accompanying drawing, forming part thereof.

Figure 1 is a front elevational view of a radio

cabinet or the like showing my new design, and having one of the doors thereof in open position.

Figure 2 is a top plan view.

Figure 3 is a right hand side elevational view.

Figure 4 is a rear elevational view.

I claim:

The ornamental design for a radio cabinet or the like, as shown.

GEORGE F. BATES.
